LEWIS B. DOMAN, OF EAST SYRACUSE, NEW YORK, ASSIGNOR TO THE AMPHION PIANO
PLAYER COMPANY, A CORPORATION OF NEW YORK.

PUMPING MECHANISM FOR SELF-PLAYING MUSICAL INSTRUMENTS.

1,149,996.

Specification of Letters Patent. Patented Aug. 10, 1915.

Application filed March 20, 1914. Serial No. 825,950.

To all whom it may concern:

Be it known that I, LEWIS B. DOMAN, of East Syracuse, in the county of Onondaga, in the State of New York, have invented new 5 and useful Improvements in Pumping Mechanism for Self-Playing Musical Instruments, of which the following, taken in connection with the accompanying drawings, is a full, clear, and exact description.

10 This invention relates to certain improvements in pumping mechanism for self-playing musical instruments and refers more particularly to the relative association of separate wind-inducing devices of pneumatically operated instruments, whereby either device may be operated independently of the other through the medium of a wind-chest common to both devices.

The main object is to enable the same instrument to be operated from separate 20 sources of power, as for example a pedal operated wind-inducer and a motor driven wind-inducer, both embodied in the same instrument in compact space and in such manner that either may be operated individually without in any way disturbing the assemblage of parts of the other device.

Another object is to enable the pedal mechanism to be folded or adjusted into 30 approximately the same plane as the motor driven bellows when not in use.

Other objects and uses relating to specific parts of the apparatus will be brought out in the following description.

35 In the drawings—Figure 1 is a front elevation of the combined wind-inducing devices, a portion of the front side of one of the motor driven bellows being broken away to show one of the interior valves. Fig. 2 is 40 a transverse vertical sectional view taken on line 2—2, Fig. 1. Fig. 3 is an enlarged transverse sectional view through one of the bearings for the motor driven countershaft for operating the corresponding power bellows.

45 As illustrated, this apparatus comprises separate sets of wind-inducing devices or power bellows—1 and —2—having fixed sides—3 and —4—rigidly secured respectively to the front and rear sides of a wind-

chest—5—which communicates with their respective power bellows through air passages—6 and —7—.

These power feeders are made in the form of bellows and are disposed side by side in an upright position, the pedal-operated feeders being arranged in one plane at the rear of the wind-chest—5—while the motor operated feeders are arranged in another plane at the front of said wind-chest.

The pedal operated bellows—1—have the lower ends of their stationary sides rigidly secured to a foot bracket or base—8—in the lower part of the instrument case, as A, said bellows being provided with movable sides—3—hinged at their upper ends to the stationary inner sides—3—so as to permit their lower ends to be moved backward and forward by suitable pedal mechanism hereinafter described.

The motor driven bellows—2—have their rear stationary sides rigidly secured to the front face of the wind-chest—5—which is supported by the stationary inner wall or side of the pedal bellows—1—, said motor driven bellows being provided with front movable sides—9—hinged at their lower ends to the corresponding ends of the stationary inner sides—4—so as to permit their upper ends to be moved backward and forward.

The inner sides of the stationary walls—3— and —4— of the respective bellows—1— and —2— are provided with additional air passages—10— and —11— communicating with the atmosphere in a space—12— between the separate sets of bellows and below the wind-chest—5—.

The ports—6— and —7— are provided with suitable valves—13— and —14— located within their respective bellows and across the adjacent ends of their ports so as to open automatically when said bellows are distended; and thus permit air to be drawn from the interior of the wind-chest—5— which may communicate in any suitable manner with a player action, not shown, said valves closing automatically by the collapse of their corresponding bellows to prevent re-entrance of air into said wind-chest. Simi- 100

lar valves —15— and —16— are provided for the inner ends of the ports —10— and —11— to open said ports automatically and allow the escape of air from their interiors to the atmosphere when they are collapsed and to prevent reentrance of the air into the bellows when they are distended. It, therefore, follows that these bellows operate as suction pumps to withdraw air from the interior of the wind-chest —5— for the purpose of maintaining a partial vacuum in the action referred to.

The pedal-operated bellows, of which there are two, are of relatively large area as compared with that of the motor driven bellows —2—, but this difference in area is compensated for by increasing the number of the motor driven bellows, of which there are six, arranged in groups of three each, some distance apart at opposite ends of the wind-chest to permit the operation and folding of the pedal mechanism. This pedal mechanism comprises a pair of pedals —17— arranged side by side and hinged at their lower ends to a cross-bar —18—, their upper ends being pivotally connected to the front ends of links —19—, which, in turn, are pivotally connected to suitable brackets —20— on the lower ends of the movable sides of their respective bellows —1—, the cross-bar —18— being mounted at its opposite ends upon suitable supporting feet or legs —21— adapted to rest upon the floor in front of the case A when the pedal mechanism is adjusted for use.

The legs —21— are pivotally connected to the front ends of a pair of links —22— which, in turn, are pivotally connected at their rear ends to brackets —23— on the front stationary sides of the bellows —1— near their lower ends so as to permit the entire pedal mechanism, including the links —19— and —22— and pedals —17— to be folded upwardly and rearwardly between and in substantially the same plane as the opposite groups of motor driven bellows —2—, to which position said mechanism would be adjusted when not in use.

When the pedal mechanism is adjusted for use, the operation of the pedals serves to distend their respective bellows —1— against the action of a retracting spring —24—, but when folded upwardly and rearwardly to the inoperative positions lie in close proximity to the front face of the wind-chest —5— between the opposite groups of motor driven bellows —2— with sufficient clearance to allow the adjacent motor driven bellows to be operated without interference with any part of the pedal mechanism.

The wind-chest —5— extends across the front faces of the pedal operated bellows —1— and across the backs of the motor driven bellows —2—, and is of sufficient

length to receive and support an equalizer —25— at one side of and in substantially the same plane as the pedal bellows and also communicating with the wind-chest through suitable ports similar to the ports —6— for equalizing the air tension in the action, in a manner well known to those skilled in this art, the equalizer being of substantially the same height as that of the pedal operated bellows.

The motor bellows —2— preferably extend some distance above the wind-chest and pedal operated bellows —1— and may be driven by any suitable motor driven mechanism comprising, in this instance a rotary shaft —26— journaled in suitable bearings —27— lengthwise of and above the wind-chest —5— and pedal-operated bellows —1— at the rear of the bellows —2— and provided with a pulley —28— adapted to be connected to an electric motor or other power driven device, said shaft being provided with a plurality of bellows-actuators, as eccentrics —29—, rigid thereon, one for each of the bellows —2— and each operating upon or against a contact plate —30— carried by the movable side of the corresponding bellows. These contact members are yieldingly held in engagement with the peripheries of their respective cams or eccentrics by retracting springs —31— connected at one end to suitable shoulders —32— on the brackets and at their opposite ends to upstanding pins —33—, which, together with the bearings —27—, are supported upon rearwardly projecting arms —34— of a stationary bracket —35—, the latter being secured to the rear faces of the stationary sides of the bellows —2— or may be secured to any other fixed support forming a part of the wind-inducing device.

The bearings —27— are swiveled in yokes —36— adjusted by means of screw trunnions —37— to allow said bearings to automatically adjust themselves in alignment with the shaft, the yokes —36— being provided with spindles —38— adjustable vertically and rotarily in suitable sockets or bearings —39— in the arms —34— to additionally facilitate the proper adjustment and alignment of the shaft, the yokes being held in their adjustable position by set screws —40—.

It will be seen from the foregoing description and the accompanying drawing that the entire wind-inducing device, comprising both sets of power bellows and their operating mechanisms, are assembled as a unit and as such are capable of being easily and quickly installed within a compact space in the case of the instrument and while I have shown a definite number in each group and spaced apart a sufficient distance to receive the pedal mechanism between them, I do not wish to limit myself

to any particular number of motor driven bellows, nor to the division of such bellows into groups.

Furthermore, I do not wish to limit myself to the use of eccentrics for driving the motor-operated bellows as it is clearly evident that other equivalent devices may be employed without departing from the spirit of my invention.

10 What I claim is:

1. In a self-playing musical instrument, a wind-chest, pumping bellows secured to the front of the wind-chest, a separate pumping bellows secured to the rear face 15 of the wind-chest, and separate operating devices for said bellows.

2. In a self-playing musical instrument, a wind inducing device comprising a wind-chest, motor driven pumping bellows secured to one side of the wind-chest some distance apart to form an intervening pedal-receiving space, pedal operated pumping bellows secured to the opposite side of the wind-chest, and pedal operated means for 25 the last-named bellows movable into and out of said space.

3. In a self-playing musical instrument, a wind chest, a pedal-operated pumping bellows secured to the rear side of the wind

chest and opening directly into the wind 30 chest, a motor driven bellows secured to the front side of the wind chest and also communicating directly therewith.

4. In a self-playing musical instrument, the combination with a wind chest, pedal-operated pumping bellows secured to one side of the wind chest and communicating directly therewith, separate pumping bellows secured to the opposite side of the wind chest and also communicating directly 40 therewith, a motor-driven shaft extending lengthwise of and above the wind chest, and pedal-operated pumping bellows, and means for transmitting motion from said shaft to said separate bellows.

45 5. In a self-playing musical instrument, a wind-chest, separate sets of pumping bellows secured to opposite sides of and communicating with the wind-chest, pedal mechanism for operating one set located in 50 the vertical plane of the other set, and separate operating means for said other set.

In witness whereof I have hereunto set my hand this 16th day of March, 1914.

LEWIS B. DOMAN.
